UNITED STATES PATENT OFFICE.

CHARLES F. ELLISON, OF CRISTOBAL, PANAMA, CANAL ZONE, AND EDWARD F. BEYER, OF NEW ORLEANS, LOUISIANA.

BOAT-LAUNCHING DEVICE.

Application filed September 15, 1922. Serial No. 588,326.

To all whom it may concern:

Be it known that we, CHARLES F. ELLISON and EDWARD FLOOD BEYER, citizens of the United States, and residing, respectively, at 5 Cristobal, Panama, Canal Zone, and New Orleans, parish of Orleans, and State of Louisiana, have invented certain new and useful Improvements in Boat-Launching Devices, of which the following is a specification.

The subject matter of the invention relates particularly to means for launching boats from steamships and is particularly designed for use while the steamship is under way. 15 The primary object of the invention is the provision of a launching device of this character which is operative with comparative safety regardless of the position of the ship whether rolling in a seaway or in calm waters. And for this purpose means are provided for retaining the boat in proper position as it is being launched and guiding the boat down the ship's side to the surface of the water in such manner that the boat is 20 prevented from swinging with relation to the ship. Novel means are provided for automatically releasing and floating the boat from its launching devices or supports when the boat reaches the water's surface.

While in launching position, the boat and its load are supported on the launching device, and the boat is held by its own weight, in locked position in its support which is the launching device. The release of the boat 30 from its launching device is automatically accomplished as the load and support of the boat is shifted from the launching device to the water when the boat reaches and floats on the surface of the water.

40 The construction of the launching device involves a comparatively small number of parts; the device is compactly arranged and ready for instant use, and may be manipulated with facility by a minimum number of hands or members of the crew.

The invention consists in certain novel combinations and arrangements of parts as will be hereinafter more fully pointed out and claimed.

50 In the accompanying drawings one com-

plete example of the physical embodiment of the invention is illustrated wherein the parts are combined and arranged according to the best mode so far devised for the practical application of the principles of the invention. 55

Figure 1 is a view in side elevation at the side of a ship showing the life boat in position to receive passengers and ready for launching.

Figure 2 is a transverse sectional view 60 showing so much of a ship as is necessary to illustrate the relation of parts, the lifeboat being shown stowed away in normal position on the boat-deck of the ship, and in dotted lines shown as water borne, just before it is 65 automatically released by the act of flotation.

Figure 3 is an enlarged detail view looking at the bow of the boat, as in position of Figure 1, with the boat supported in the 70 launching device.

Figure 4 is a view similar to Figure 3 showing the relation of parts after the boat because of its flotation has automatically released itself from the launching device. 75

Figure 5 is a detail, top plan view of one of the supporting cradles of the launching device.

Figure 6 is an enlarged, detail, sectional view showing the cradle locking device 80 whereby the boat is supported, and the keel of the boat holding the device in locked position.

In order that the relation of parts may readily be understood the boat deck of a steamship is indicated at 1 and the side of the ship is designated as 2. The launching device includes two pairs of flanged plates as 3 and 4 riveted or otherwise secured to the outside of the ship and extending, as at 5 a sufficient distance inboard at the boat deck 1. These pairs of plates are spaced the required distance apart in parallelism, and the plates of the pairs are spaced apart to form retaining and guiding grooves for the movable members of the launching device, which include a forward cradle 6 and an after cradle 7, that are openable as will be described. 95

The cradles are of proper size and shape 100

to support the boat 8, which may be a life boat of standard or usual type and is designed to be lowered or raised, while supported in the complementary cradles, along 5 the side of the ship. As the construction and operation of the two cradles are the same, a description of one together with the identification of its parts will suffice for both cradles.

10 Each cradle is fashioned with an outwardly and upwardly curving leg 9 having a lower end lug or foot 10 which is of correct size and shape as to slide freely in the groove or guideway formed by the flanged plates 3 and 4. A reversely curved, inboard arm 11 is formed integral with the leg 9 and this arm is fashioned with a lug or head 12 similar to the foot 10 of the leg 9, and guided in the guide ways 3 and 4. Thus the rigid portions 15 of the cradles formed by the arms 11 and legs 9 have movable attaching and guiding means for holding the cradles in upright position as it is lowered or hoisted along the side of the ship.

20 Each cradle is provided with a suspending shackle 13 swiveled to the head 12, and in Figure 1 a wire bridle 14 is shown connected to these spaced shackles, to which 25 the wire cable or rope 15 is connected. The launching cable 16 is normally wound on the drum 16 of a winch or other hoisting mechanism, and may pass over one or more guide rollers or sheaves 17 located at required points on the ship for guiding 30 and permitting free movement of the launching cable. The winch is controlled in usual manner by a friction brake or clutch for controlling the movement of the cable and may be manned by a single member of the 35 crew.

40 As best seen in Figures 3 and 4, the cradles are openable to permit flotation of the boat when the latter has been lowered by the cradles to the water's surface, and the 45 retaining or locking means which hold the cradles closed, are automatically released as soon as the boat is floated, thus permitting the opening movement, by gravity, of the cradles to free the boat.

50 Each cradle has an outboard arm 18 fashioned with a head 19, the arm being curved in shape, complementary to the inboard arm 11, to form a support for the boat and hold the latter in upright position. The head 19 is pivoted at 20 and fits into a socket 21 formed at the juncture of the arm 11 and leg 9, and when not retained by positive means 55 the outboard arm is of sufficient weight to cause a swinging movement to open position as in Figure 4. Within the head 19 of the arm is carried a locking bolt 23 adapted to slide in the bolt-socket 22, and a bushing 24 is fixed in the socket as a housing for the locking bolt, which slides and is guided 60 therein in its movements. At one end the

slide bolt is beveled to form a locking head 25 adapted to engage the keeper-notch 26 formed as an extension in one of the walls of the socket 21, and at the other end of the bolt a spring 27 is interposed between the 70 bushing 24 and the enlarged head 28 of the bolt. The retracting spring 27 tends to withdraw the beveled locking head 25 from its keeper notch 26, and urges the bolt back 75 into its socket, except when the latter is held in projected position by a latch member 29.

80 The latch is pivoted at 30 and is carried by the head 19 of the arm 18, with its lower or inner end located in a transverse slot 31 that extends longitudinally of the locking bolt 23. The outer end of the latch is fashioned with a head 32 in position to be engaged by the bottom of the keel of the boat, as 33. Thus in Figure 6, where the parts are locked together, it will be seen that the slide bolt is directly engaged with the cradle to hold the pivoted arm 18 in upright position, the bolt is engaged by the latch to hold the former in projected position, and 85 the latch is engaged by the keel of the boat to hold the latch immovable. When the keel of the boat is withdrawn from contact with the latch, the spring 27 retracts the bolt, swinging the latch on its pivot, thus 90 releasing the head 19 of the arm 18, and the arm then falls, by gravity, swinging on its pivot 20, and falling away from the outboard side of the boat.

95 As before stated this unlocking and releasing movement is accomplished by flotation of the boat and the relief of its load from the latch, thereby freeing the boat from the cradles.

100 In launching the boat from the upper position of Figure 2, the lashings or other securing means for retaining the boat in its cradles are first released. The boat is then pushed with its cradles off the boat deck and lowered to position, as in Figure 1, to 105 receive passengers. Preferably the boat is suspended from the wire cable and bridle with its stern slightly lower than the bow, i. e. the after cradle being slightly lower than the forward cradle due to proper arrangement of the bridle. When lowering away the rudder is shipped and a man placed at the tiller, and as the stern strikes the water before the bow of the boat, the 110 rudder is immediately effective when the tiller is turned toward the ship, to steer the boat from the ship's side. As the boat is floated, it is automatically released from its cradles as described.

115 Should the launching occur while the ship is rolling, it will be apparent that the boat is held safely suspended in its cradles until the proper instant when the list of the ship floats the boat on the surface of the water.

120 When the launching occurs while the ship 125

is under way no time is lost in preparing to launch, as, for instance at the warning of "man overboard," the boat may be launched with the steamship under full speed, and 5 the boat, which is automatically released as it strikes the water, may then be steered without loss of time to the person overboard. In such case, the fact that the stern of the boat strikes the water first and the bow is 10 elevated, prevents the boat from being submerged when forward movement is imparted thereto by the forwardly moving ship, and also insures that the rudder may take hold in the water instantly for steering and 15 controlling the movement of the boat.

From the above description taken in connection with our drawings it will be apparent that the device of the invention is fully capable of performing its functions with 20 safety, reliability and dispatch, and in a shipshape manner.

Having thus fully described the invention, what is herein claimed is:—

1. A boat launching device having a movable member and retaining means for holding said member in operative position for supporting a boat, and locking means carried by the cradle and in contact with the boat held in locking position by the weight 25 of the boat, and an automatic unlocking device for the bolt operative upon the release of the bolt from the force of gravity of the boat.

2. In a boat launching device the combination with suspending means, of boat supporting devices each having a movable member, and locking means carried by the cradle and in contact with the boat held in locking position by the weight 30 of the boat, and an automatic unlocking device for the bolt operative upon the release of the bolt from the force of gravity of the boat.

3. In a boat launching device, the combination with suspending means, of a boat supporting device adapted for submersion and locking means carried by the cradle and in contact with the boat held in locking position by the weight of the boat, 45 and an automatic unlocking device for the bolt operative upon the release of the bolt from the force of gravity of the boat.

4. The combination with a suspending device of a pair of boat-supporting cradles 50 each including a releasable member adapted to be freed when the boat is floated, and locking means carried by the cradle and in contact with the boat held in locking position by the weight of the boat, and an 55 automatic unlocking device for the bolt operative upon the release of the bolt from the force of gravity of the boat.

5. The combination in a boat launching cradle having a releasable member, of lock-

ing means carried by the cradle and in 65 contact with the boat held in locking position by the weight of the boat, and an automatic unlocking device for the bolt operative upon the release of the bolt from the force of gravity of the boat. 70

6. The combination in a boat launching cradle having a releasable supporting arm 75 adapted to be released upon flotation of a boat, and locking means carried by the cradle in contact with the boat held in locking position by the weight of the boat, and an automatic unlocking device for the bolt operative upon the release of the bolt from the force of gravity of the boat.

7. The combination with a pair of cradles 80 and suspending means therefor, of a releasable supporting arm on each cradle, and locking means carried by the cradle in contact with the boat held in locking position by the weight of the boat, and an automatic 85 unlocking device for the bolt operative upon the release of the bolt from the force of gravity of the boat.

8. The combination with spaced tracks, suspending and lowering means, a pair of 90 cradles and means for guiding said cradles in said tracks, of a releasable supporting arm on each cradle, and locking means carried by the cradle in contact with the boat held in locking position by the weight of 95 the boat, and an automatic unlocking device for the bolt operative upon the release of the bolt from the force of gravity of the boat.

9. In a launching device, the combination with a fixed track, of a cradle having a rigid arm and leg guided in said track, a 100 releasable arm on said cradle, and locking means carried by the cradle in contact with the boat held in locking position by the weight of the boat, and an automatic 105 unlocking device for the bolt operative upon the release of the bolt from the force of gravity of the boat.

10. The combination in a boat launching cradle having a slideable arm and leg and guiding means therefor, of an arm pivoted in said cradle and a locking bolt carried thereby adapted to engage the cradle, and locking means carried by the cradle in contact with the boat held in locking position by the weight of the boat, and an automatic 110 unlocking device for the bolt operative upon the release of the bolt from the force of gravity of the boat. 115

11. The combination in a boat launching cradle having a pivoted supporting arm and a complementary fixed arm, of a locking bolt carried by the pivoted arm and adapted to engage the cradle, a pivoted 120 latch carried by the pivoted arm for engaging said bolt, and said latch being in contact with and adapted to be held in 125

position by the weight of a boat for retaining the bolt in locked position.

12. The combination with spaced grooved, fixed tracks, of a pair of spaced launching cradles each having a rigid arm and leg and lugs on said members slidable in said tracks, a pivoted supporting arm on each cradle,

spring-pressed locking bolts carried by said pivoted arms, and a latch on each pivoted arm in contact with the boat and adapted by the weight of a boat to hold the locking bolts in operative position.

CHARLES F. ELLISON.
EDWARD F. BEYER.
